UNITED STATES PATENT OFFICE.

PIÈRRE HAERST, OF CHICAGO, ILLINOIS.

STREET-SWEEPER.

SPECIFICATION forming part of Letters Patent No. 625,163, dated May 16, 1899.

Application filed February 1, 1899. Serial No. 704,093. (No model.)

To all whom it may concern:

Be it known that I, PIÈRRE HAERST, a citizen of the United States, residing at Chicago, in the county of Cook and State of Illinois, have 5 invented certain new and useful Improvements in Street-Cleaning Machines for Boulevards, Parks, and Paved Streets, of which the following, when taken in connection with the drawings accompanying and forming a 10 part of this specification, is a description sufficient to enable those skilled in the art to which it pertains to understand, make, and use the same.

This invention relates to that class of cleaners designed to gather or pick up articles, either dirt or other material, from the ground and deposit the same in a receptacle provided therefor.

The object of this invention is to obtain a 20 machine which shall be particularly arranged for and fitted to maintain park-boulevards and asphalt-paved streets in a cleanly and presentable condition; and for the purpose of carrying out the above-named object I have 25 obtained a machine whereby dirt can be picked from the ground, either street or boulevard, and deposited in a receptacle therefor carried by and forming an element in the machine. I have also obtained a machine from 30 which the receptacle used can be readily taken and another and like receptacle substituted therefor. I have further obtained a machine in which the several adjustments necessary to retain the parts in proper relative position as the machine is used and such 35 parts are worn are simple, easily made, and not liable to get out of order.

In the drawings referred to and wherein a 40 letter of reference applied to designate a given part is used to designate such part throughout the several figures wherever it appears, Figure 1 is an end elevation of a cleaning-machine embodying the invention; Fig. 2, a vertical sectional view adjacent to the driving-wheel of the machine, showing the apron and shovel and adjustable shoe of the machine in proper relative position; Fig. 3, a 45 side elevation of the upper end of the frame of the apron and of a U-shaped frame to 50 which the apron-frame is attached and to which U-shaped frame also the axles of the machine are secured; Fig. 4, an end elevation

of the lower end of the apron-frame with the several parts attached thereto; Fig. 5, a perspective view of a shoe illustrated in Figs. 55 1 and 2, which is adjustably attached to the lower end of the apron-frame when the machine is to be used on soft roads, macadamized roads, and all other than asphalt roads or streets; Fig. 6, a perspective view of a portion 60 of the brush-chain of the machine and of the brush-holder attached thereto, and Fig. 7 an end elevation of a dirt-receptacle which is removably attached to the machine.

A, Fig. 1, is the non-rotatable axle of the 65 machine, on which the wheel *a* is rotatably mounted in the ordinary way. Axle A (one on each side of the machine) is secured to the upper end of the U-shaped frame B.

b, Fig. 2, is the horizontal member of U- 70 shaped frame B, and *b'* a vertical member thereof.

*b*² is a slot in vertical member *b'* of U-shaped frame B, and *b*³ is a hole therein through which the axle A extends and is attached 75 thereto.

C is a dirt-receptacle having the projection or lug *C'* on each end thereof, respectively.

*C*² is an arm rigidly secured at one end thereof to vertical member *b'* of U-shaped 80 frame B.

*C*³ is a recess in the outer end of arm *C*², in which recess the projection or lug *C'* of the receptacle *C* rests when such receptacle is mounted on the machine. The forward part 85 of the receptacle rests on horizontal member *b* of the U-shaped frame B. The receptacle *C* will therefore maintain its position by gravity on such arms *C*² *C*³ (one on each side of the machine) and member *b* of U-shaped frame B. 90

*C*⁵ is the handle by which the machine is propelled.

D is the apron-frame of the machine.

d is a bolt extending through the apron-frame *D*, near the upper end thereof, and 95 through the slot *b*² in vertical member *b'* of U-shaped frame B.

d', Fig. 2, is the apron of the machine. Apron *d'* is secured to the apron-frame *D*, the upper end of the apron extending to above 100 the receptacle *C* when such receptacle is placed on the machine, as above described and as illustrated in Fig. 1.

*d*² is the lower end of apron *d'*, formed to

receive on the upper face thereof the upper edge of the adjustable shovel N, hereinafter described. (See Figs. 2 and 4.)

E is a side bar (there being one thereof on each side of the machine) adjustably securing the apron-frame D to the upright member b' of U-shaped frame B. The adjustment secured by the side bars E E is to obtain proper tension on the brush-chain J, hereinafter described. The adjustment of the upper end of the apron-frame D, which is obtained by bolt d extending therethrough and through the slot b² in vertical members b' b', is to obtain proper relative position between the apron d' and the brushes L, hereinafter described, at the upper end of such apron.

e is a bolt extending through the side bar E and apron-frame D, and e' is a bolt extending through slot e² in side bar E and through vertical member b' of the U-shaped frame B.

F is a wheel secured to one of the wheels a a of the machine to rotate with such wheel and having internal gear-teeth thereon.

G is a wheel secured on shaft g to rotate therewith, having external gear-teeth engaging with the gear-teeth in wheel F.

g', at the upper end of vertical member b', forms the bearing in which shaft g is rotatably mounted. (See Figs. 2 and 3.)

H H are sprocket-chain wheels rigidly secured, respectively, to shaft g on each side of the machine to rotate therewith.

H', Fig. 2, is an ordinary clutch, by means of which the wheel G is thrown into and out of engagement with the wheel F, so as to rotate or not, as preferred, the sprocket-chain wheels H, there being two sprocket-wheels H, one adjacent to each of the upright members b' b' of U-shaped frame B.

I I are sprocket-chain wheels rigidly secured to shaft i to rotate therewith. Shaft i is rotatably mounted in the frame D, near the lower end thereof, as illustrated in Figs. 1, 2, and 4.

J J are brush-chains extending, respectively, over sprocket-wheels H H I I and having secured thereon at intervals the brush sockets or frames K K.

L L are the brushes, by means of which the material gathered on shovel N is elevated on apron d' and delivered therefrom into the receptacle C in the operation of the machine.

Brush sockets or frames K K, respectively, comprise bed k, sides k' k', and turned-in edges k² k². The brushes L are inserted in the brush sockets or frames K by being forced thereinto or slid, so that when a given brush becomes worn it may be removed and a new one substituted therefor.

M, Fig. 2, is a roller mounted on shaft m in adjustable frame M' to come in contact with the chain J, adjacent to the lower end of the apron d', to adjust the brushes to the apron at such lower end of the apron.

m' is a bolt extending through slot m² of the frame M' and through apron-frame D.

By means of the adjustment last above described of the rollers M M with reference to the lower end of the apron-frame, such rollers forcing the chain to an adjusted position and the adjustment of the apron-frame D toward the brushes at the upper end of such frame by means of bolt d in slot b², hereinbefore described, any desired adjustment of the entire apron d' with reference to the brushes passing over it is obtained.

N is a shovel adjustably secured to the apron-frame B, at the lower end of such apron-frame, by means of bolt n, passing through slot n'.

n² is a loop or pocket on the under side of the shovel N, into which loop or pocket the forward end of the shoe O extends, such forward end of the shoe being lettered O³. Shoe O is adjustably secured in place by bolt O', extending through slot O³ in such shoe and through the apron-frame D, such bolt having a nut thereon.

The shoe O is not used by me when the machine is employed for gathering refuse, litter, or dirt on an asphalt-paved boulevard or street, its purpose being when used to prevent the forward edge of the shovel N penetrating a street or boulevard, when the surface thereof is soft or dusty, beyond a determined distance. To show the attachment of the forward end O³ of shoe O to the shovel N, such shovel N is shown in Figs. 1, 2, and 4 at a greater incline than I prefer to place such shovel ordinarily. Any adjustment of the incline of the shovel N is readily obtained by loosening the nut on bolt n in slot n'. (Well shown in Fig. 4.)

This machine is particularly adapted for use on park-boulevards in place of the ordinary sheet-iron scoops now employed for that purpose and is designed to be pushed by a man or boy by handle C⁵ about the street. The receptacle C is made removable, so that when the same is filled it can be lifted from the machine and placed to one side of the boulevard and a duplicate receptacle substituted therefor on the machine or to be removed from the machine at any time and the contents thereof emptied into a cart or other receptacle.

By obtaining the several adjustments hereinbefore particularly described I am able to make a machine which will well perform the work it is intended to do and so easy to manipulate and propel that a man or boy may readily move or push it about a street or boulevard and maintain the same in an acceptably clean condition even when many horses are driven thereover.

Having thus described my invention and its manner of operation, what I claim as new, and desire to secure by Letters Patent, is—

1. The combination of a frame mounted on wheels and means to propel the frame and wheels, an apron-frame adjustably secured to the mounted frame near the upper end

thereof, a receptacle removably attached to the mounted frame, an apron secured to the apron-frame to discharge from the upper edge thereof into the receptacle, a shovel adjustably secured to the lower end of the apron-frame to discharge onto the lower edge of the apron, shafts rotatably mounted in the apron-frame, a driving-wheel secured to one of the wheels of the mounted frame, a wheel removably engaging with the driving-wheel on one of the rotatably-mounted shafts, chain-wheels on the shafts, chains extending over the chain-wheels, brushes removably attached to the chains, and means for adjusting the chains and brushes relative to the lower end of the apron; substantially as described.

2. A U-shaped frame having upright members, an apron-frame attached near the upper end thereof to the upright members, near the upper ends thereof respectively, side bars adjustably attached to the apron-frame and to the upright members, a shaft having chain-wheels thereon rotatably mounted near the upper end of the upright members, a shaft having chain-wheels thereon rotatably mounted in the apron-frame near the lower end thereof, an apron, and a shovel, and chains, carrying brushes mounted thereon, such chains extending over the chain-wheels; whereby the tension of the chains is controlled by the relative position of the upper end of the apron-frame and the upper ends of the upright members through the adjustably-attached side bars; substantially as described.

3. An apron-frame, a shaft rotatably mounted in the apron-frame near the lower end thereof, chain-wheels on the shaft, a shaft rotatably mounted adjacent to the upper end of the apron-frame, chain-wheels on the last-named shaft, means for adjusting the upper end of the apron-frame relative to such shaft, an apron on the apron-frame, a shovel attached to the lower end of the apron-frame to discharge onto the apron, such shovel adjustably on the apron-frame relative to the rotatable shaft adjacent thereto, chains extending over the chain-wheels, brushes removably attached to the chains, roller-frames adjustably attached to the apron-frames adjacent to the lower end of the apron, and rollers rotatably mounted in such roller-frames

engaging with the chains; substantially as described.

4. A frame mounted on wheels, an apron-frame, a shaft rotatably mounted in the apron-frame near the lower end thereof, chain-wheels on the shaft, chains extending over the wheels, means for actuating the chains, brush-sockets attached to the chains, brushes removably secured in the brush-sockets, a shovel attached to the apron-frame adjacent to the shaft, with means for adjusting the shovel relative to the rotatable shaft, a receptacle removably attached to the mounted frame, and an apron on the apron-frame arranged to discharge into the receptacle and means for adjusting the apron relative to the brushes at the upper end of such apron; substantially as described.

5. An apron-frame, a shovel adjustably attached to the apron-frame near the lower end of such apron-frame, and shoes adjustably attached to the apron-frame, such shoes extending underneath the rear edge of the shovel and attachable to such shovel at the forward ends of the shoes; substantially as described.

6. An apron-frame, a shovel adjustably attached to the apron-frame near the lower end of such apron-frame, and shoes removably attached to the apron-frame adjacent to the shovel, such shoes being adjustable with reference to the apron-frame; substantially as described.

7. The combination of an apron, a shovel forming a continuation of the lower end of the apron, brush-chains, brushes attached to the chains, such brushes and chains passing over the shovel and apron in the operation of the machine, means for actuating the brushes and brush-chains, means for adjusting the brushes and brush-chains relative to the apron at the lower edge of the apron, means for adjusting the apron relative to the brushes and chains at the upper edge of the apron, and means for adjusting the shovel relative to the brushes and chains substantially as described.

PIÈRRE HAERST.

In presence of—

CHARLES TURNER BROWN,
FLORA L. BROWN.
